UNITED STATES PATENT OFFICE.

GEORGE A. LE FEVRE, OF RICHMOND HILL, NEW YORK, ASSIGNOR TO PAXFLAT BARREL & CRATE CORPORATION, OF NEW YORK, N. Y., A CORPORATION OF NEW YORK.

KNOCKDOWN BARREL.

Application filed January 5, 1922. Serial No. 527,085.

To all whom it may concern:

Be it known that I, GEORGE A. LE FEVRE, a citizen of the United States, and a resident of Richmond Hill, Queens County, New York, have invented a new and useful Improvement in Knockdown Barrels, of which the following is a full, clear, and exact description.

My invention relates to improvements in knock down barrels, and more particularly to the body portion of such barrels. To be still more definite, my invention relates to knock down barrels of the type in which the body portion is formed of staves which 10 abut edge to edge, are adapted to lie flat for shipping or storage, or to be rolled up into barrel form for use. It is desirable in structures of this kind to have the hoops which fasten the body in operating position and 15 hold the heads, movable with relation to the staves, as this facilitates the adjustment of the hoop. Moreover, when the hoops and staves are fastened together there is a strain on the fastening attachments which tends 20 to tear the hoops from the staves and injure the structure. My invention is intended to produce a barrel body of this general kind which can be more conveniently handled and set up for use, or handled for storage 25 or shipping, than where the staves and hoops are secured together and reliance is made on the hoop and stave connection for keeping the parts in shape. I have found that by 30 attaching the several staves firmly together 35 edge to edge and in the right relation by a flexible means which will form the body into a sort of mat which can be conveniently handled, the barrel can be used to much better advantage and handled more economically. 40 This will appear clearer from the description which follows.

Reference is to be had to the accompanying drawings forming a part of this specification, in which similar reference characters 45 indicate corresponding parts in all the views.

Figure 1 is a side elevation of a set up barrel embodying my invention.

Figure 2 is an enlarged broken inside elevation of two adjacent staves.

Figure 3 is an end view of the structure shown in Figure 2, with the staves at an angle to each other to engage at the edges.

Figure 4 is a view similar to Figure 3 but with the staves laid flat.

Figure 5 is a broken exterior view of the barrel body when laid flat, and

Figure 6 is a broken inside view of the flat barrel body.

By way of example I have illustrated my improved construction in connection with a knock-down barrel having staves 10 arranged edge to edge, and provided with croze grooves 11 to receive the heads, and at the edges the staves have inclined recesses 12 spaced apart, and with square shoulders 13 between the recesses, the recesses on one edge being in staggered relation to those on the other edge of the staves, so that the staves will always meet at their outer edges, but when bent up as in Figure 3, to form a barrel, the shoulders 13 will enter the recesses 12, and so lock the staves together against end-wise movement.

I have referred to the foregoing structure in order that my invention may be better understood, but this is not here claimed as it is covered in an application for Letters Patent of the United States Serial No. 403,468, filed August 14, 1920, and allowed November 3, 1921.

In my prior construction, and in most knock down barrels, the staves are held in the right relation by the hoops 14; whereas in my present structure, the hoops are independent of the barrel body, being simply guided through staples 14^a which can be placed at necessary intervals, a few being spaced around the barrel, and the hoop ends are fastened together by a suitable fastening shown at 16.

I have found, however, that if the staves when laid flat have an exterior fastening which holds them together to form a flexible mat or body, the body can be handled much more conveniently and economically. To this end I provide them with thin metallic bands 17, which are spaced apart and firmly secured to the staves, these bands being simply long enough to extend across the flat body as in Figure 5, but they have nothing to do with holding the barrel together when set up. They simply serve the purpose of facilitating the handling of the flat body, or the body which is not secured in barrel form. I have shown two of these bands as being a convenient number, and I prefer to use flat metallic bands, but so far as the invention is concerned, these mem-

bers 17 might be wires, or in fact any means of holding the staves in the right relation before the barrel is set up for use; and so far as this invention is concerned, the parts 12 and 13 are not particularly material, although my structure lends itself well to this type of barrel.

It will be seen that the members 17 are sufficiently flexible to allow the barrel to be rolled up into generally cylindrical shape, or to tie out flat, and the body when the staves are fastened together as specified, forms a simple flexible unit which can be handled with great facility. When it is set up, the usual heads are placed in the croze grooves, and the hoops 14 are secured at the

ends as at 16. I have shown three hoops, but any desired number can be used, and likewise any desired number of the fastening members 17 can be used to hold the staves together.

I claim:—

A flexible body blank for knock down barrels comprising staves placed together edge to edge and transverse flexible members lacking the functional characteristics of a hoop secured to the staves to hold them in the right relation.

GEORGE A. LE FEVRE.
